UNITED STATES PATENT OFFICE.

FREDERICK G. GRUEN, OF CINCINNATI, OHIO.

DESIGN FOR A WATCHCASE OR SIMILAR ARTICLE.

SPECIFICATION forming part of Design No. 35,407, dated December 10, 1901.

Application filed October 3, 1901. Serial No. 77,506. Term of patent 7 years.

To all whom it may concern:

Be it known that I, FREDERICK G. GRUEN, a citizen of the United States, residing at Cincinnati, in the county of Hamilton and State of Ohio, have invented and produced a new and original Design for Watchcases or Similar Articles; and I do hereby declare the following to be a full, clear, and exact description of the same, reference being had to the accompanying drawings, forming a part thereof.

My invention relates to a design for a watchcase or similar article; and it consists of the shape, configuration, and ornamentation shown in the accompanying drawings, in

which—

Figure 1 is a plan view, and Fig. 2 an edge view.

The leading or material feature of my design consists of a watchcase provided with an ornamentation comprising an aggregation of fine substantially parallel but jagged ridges and grooves covering substantially the entire surface of the case, as shown at A, except a small space left plain and shown in the form of a shield at B.

What I claim is—

The design for a watchcase or similar article substantially as shown and described.

In testimony whereof I affix my signature in presence of two witnesses.

FREDERICK G. GRUEN.

Witnesses:

A. H. ERNST,
D. GRUEN.
